UNITED STATES PATENT OFFICE.

OTTO WILHELCI, OF KÜSNACHT, SWITZERLAND.

COVERING FOR CABLES AND SIMILAR DEVICES.

No. 801,494.

Specification of Letters Patent.

Patented Oct. 10, 1905.

Application filed March 31, 1905. Serial No. 253,054.

To all whom it may concern:

Be it known that I, OTTO WILHELCI, a citizen of the Swiss Republic, residing at Küs-
nacht, near Zurich, Switzerland, have invent-
ed new and useful Improvements in Coverings
5 for Cables and Similar Devices, of which the
following is a specification.

This invention relates to an improved cov-
ering for cables, wires, pipes, and other trans-
mitters which is strong, flexible, and tight, so
10 as to effectively shield the inclosure against
moisture and other injurious influences.

In the accompanying drawings, Figure 1 is
15 a side view of a cable, showing the covering
in section; Fig. 2, a plan thereof; Fig. 3, a
cross-section on line A. B, Fig. 2. Fig. 4 is a
plan of the covering, showing it spread out in
a plane; and Fig. 5, a side view of a cable,
20 showing two layers of the covering in section.

The letter *a* represents a flexible sheet or
wrapper adapted to be wound around a cable *k* and composed of tar-paper or other wa-
terproof material. Into the wrapper *a* are
25 woven a series of parallel flexible metal bands
b by being passed alternately upward and
downward through transverse slits *a'* of the
wrapper. Each band *b* thus projects alter-
nately over the top and bottom of the wrap-
per, so that in this way the entire wrapper is

30 armored, though free to bend in a longitudi-
nal direction between adjoining bands. The
transverse slits *a'* of adjoining bands break
line with each other, as shown, to prevent an
undue weakening of the wrapper along trans-
verse lines.

35 My improved covering is especially adapt-
ed for underground cables, water-pipes, gas-
pipes, and drains and effectively protects the
same against frost, moisture, and other inju-
rious influences.

40 What I claim is—

1. A protective covering for cables and
similar devices, composed of a waterproof
wrapper having transverse slits, and of par-
allel metal strips passing through said slits, 45
substantially as specified.

2. A protective covering for cables and
similar devices, composed of a waterproof
wrapper having transverse slits arranged to
break line, and of parallel metal strips pass- 50
ing through said slits, substantially as speci-
fied.

Signed by me at Zurich, Switzerland, this
16th day of March, 1905.

OTTO WILHELCI.
